FIG. 1

FIG. 2

INVENTOR
G. C. ADAMS

or Wright & Chesser

ATT'YS.

UNITED STATES PATENT OFFICE.

GEORGE C. ADAMS, OF SAN FRANCISCO, CALIFORNIA.

OIL-FURNACE FOR BOILERS.

1,382,402.

Specification of Letters Patent. Patented June 21, 1921.

Application filed May 22, 1920. Serial No. 383,350.

To all whom it may concern:

Be it known that I, GEORGE C. ADAMS, a citizen of the United States, residing at San Francisco, in the county of San Francisco 5 and State of California, have invented new and useful Improvements in Oil-Furnaces for Boilers, of which the following is a specification.

This invention relates to improvements in 10 furnace construction for oil burning boiler furnaces and the primary object of the invention is to provide for better combustion and greater heat at a relatively low fuel consumption; to provide a steady flame whether 15 large or small; to eliminate smoke and noise; and to permit of an effective control of the flame at all times.

The invention possesses other advantages and features, some of which, with the foregoing, will be set forth at length in the following description wherein I shall outline in full that form of the invention which I have selected for illustration in the drawings accompanying and forming a part of the present specification. In said drawings, I have shown one form of the construction of my invention, but it is to be understood that I do not limit myself to such form, since the invention as expressed in the claims may be 30 embodied in a plurality of forms.

Referring to the drawings:

Figure 1 is a fragmentary longitudinal sectional view of the furnace floor of my invention.

35 Fig. 2 is a top plan view of the furnace floor shown in Fig. 1.

Fig. 3 is a fragmentary longitudinal sectional view of the furnace of my invention, on a reduced scale, and showing part of a 40 horizontal boiler.

In carrying out my invention, I construct and arrange the floor of the furnace so that it inclines downwardly from a point beneath the furnace toward the mediate portion 45 thereof, in steps or stages, and at certain points in this inclined floor, I provide upwardly diverging relatively large air inlet openings. The flame is directed longitudinally from the burner over the inclined floor 50 and in part directs downwardly and a short distance forwardly over the first step or stage of the inclined floor and then passes horizontally forwardly over the second stage of the inclined surface. It is preferably in 55 this second stage that the diverging openings are formed and air entering the furnace

from below the floor through said openings quickly expands due to the upward divergence of the openings. By this expansion and the large openings provided, the large 60 volume of air admitted is more readily heated due to its having expanded and as the flame does not pass close to the air openings but horizontally above them, the air is given more time in which to expand and heat and 65 to mix with the fuel gases burning in the furnace. In this way I am permitted to introduce and consume a larger volume of air than is the case with the ordinary oil furnace, without smothering the air ports and 70 as a result consummate a saving in fuel and provide an effective and even greater heat.

In the ordinary oil burning furnace for 75 boilers, the flame passes directly over and close to small, straight, or parallel sided air 80 openings in a flat furnace floor and the flame tends to smother the ports or openings with the result that not enough air is admitted to properly support combustion. Furnaces of this type are difficult to manage under a 85 small flame and when overloaded smoke and make an objectionable noise. The flame in either instance is unsteady. With my improved furnace construction such as described, these objections are eliminated and less fuel need be consumed to provide heat equal to or even greater than said prior furnaces.

Other features of novel construction of my 90 furnace aid in removing the objections and generally improving oil burner furnaces for 95 boilers and will be hereinafter described in detail.

In the present embodiment of the invention, the furnace 4 is generally of the ordinary type, having doors 5 with which the air admitted to the furnace is regulated and having an oil burner 6 projecting horizontally into the furnace through the door end 7 of the furnace, above said doors.

The floor 8 of the furnace, generally speaking, is raised at the front end of the furnace to provide an air chamber 9 and the portion thereof under and in line with the burner is inclined downwardly toward the 100 center of the furnace at which point a combustion pit 10 is formed. From the upper side of this pit, the floor is slightly upwardly inclined toward the rear of the furnace. This floor arrangement permits the 110 gases to expand slowly and in this way reduces the noise. This pit 10 has the effect

of giving the fuel gases a "twist" in permitting expansion thereof, with the result that the air is thoroughly mixed with the gases and a thorough combustion follows; 5 also, this retards the movement of the flame and provides an intense heat throughout the furnace.

The downwardly inclined portion of the 10 floor comprises a first stage or step 11 directly under the burner and is supported by pipes 12 extending transversely in the furnace. This portion 11 is for example, two feet wide and terminates forwardly, for example, a little over a foot, say, one foot six 15 inches in front of the burner. At a point on either side of this portion 11 rearwardly of, and below, the inclined surface, there are provided large air ports 13 communicating with the air chamber 9. In front of these 20 openings on opposite sides of the portion 11 are two or more rows of fire brick 13' over which air passes from the openings 13. On top of the step or portion 11 on each side of the burner are baffle members 14 which 25 diverge forwardly and are preferably formed of fire brick. Air entering through the ports or openings 13 passes between and behind these baffles into the furnace and around the sides and in front of said 30 baffles. These baffles become heated and heat the air passing around and between them. By being diverged the flame and fuel gases expand between the baffles and are prevented by the baffles from being smothered by too 35 great an inrush of air from behind the burner. This will permit of the firing of a small flame, which flame will be clear, intense and steady.

The second step 15 of the inclined floor 40 is of substantially the same width and length as the first stage but these proportions may be varied as desired. The stage begins from a point preferably one-half inch below the lower end of the first stage and preferably 45 comprises rows of fire brick 16, in one layer, which bricks are spaced in transverse rows to provide a plurality of transverse air intake openings 17 in said stage. The sides of the bricks of each row are beveled so as to 50 provide upwardly enlarging or diverging openings. The bricks are suitably supported, preferably by pipes 18 and this stage of the floor is inclined downwardly and forwardly, but not to the extent of inclination 55 of the first stage. The floor on the side of this stage is closed and solidly formed as in the ordinary furnace. Rows of fire brick 19 are placed on the sides of the stage 15 and extend horizontally as walls above the 60 top surface of the openings 17 to concentrate and confine the air to the area above the openings 17 and under flame.

The third stage 20 is not inclined but 65 level and disposed about six inches below the lower end of the second stage with its for-

ward edge defining the upper edge of the combustion pit 10.

In operation, the fuel is ignited at the burner and air from the chamber 9 passes upwardly into the furnace through the openings 13 and 17. The flame flares laterally and downwardly, the latter, over the inclined surface of the first stage 11 and then is directed forwardly substantially horizontally. The draft thus created causes air to 75 be drawn into the furnace through the openings 13 and the air passes between the baffles 14 and around said baffles over the fire brick 13' into the furnace. By arrangement of the baffles 14, and ports 13 relative to the 80 burner the air is divided, allowed to expand and is heated whereby it will readily support combustion of the fuel. As the air enters through the converging openings 17 in the second stage 15, it expands and is readily heated, the space between the openings and the flame owing to the inclination of this stage permitting the air to enter the flame and to mix with the combustible gases more readily as previously described. 85

The next stage 20 is being below the other stage permits the flames to expand slowly. The pit 10 causes scattered combustible particles to be swirled therein and gives a twist to the flame, whereby thorough combustion 95 is provided.

I claim:—

1. An oil burning furnace including a burner, a floor having a downwardly inclined surface below the burner and extending in front of the burner, and another downwardly inclined surface extending from the first surface, said latter surface having a plurality of upwardly opening air intake openings therein. 100

2. An oil burning furnace including a burner, a floor having a downwardly inclined surface below the burner and extending in front of the burner and another downwardly inclined surface extending 110 from the first surface, said latter surface having a plurality of upwardly opening air intake openings therein, said opening having upwardly diverging sides.

3. An oil burning furnace including a 115 burner, a floor having a downwardly inclined surface below the burner and extending in front of the burner, and another downwardly inclined surface extending from the first surface, said latter surface 120 having a plurality of upwardly opening air intake openings therein, said opening having upwardly diverging sides, and a combustion pit in said floor beyond and below the level of the second inclined surface. 125

4. An oil burning furnace comprising an end wall, a floor extending forwardly from a point above the lower side of the end wall and being inclined downwardly toward a mediate point of the floor, there being an air 130

chamber below the inclined part of the floor, said floor having air intake openings in the inclined portion thereof, and a burner disposed above and in line with the inclined 5 portions, said air openings being diverged upwardly.

5. An oil burning furnace comprising an end wall, a floor extending forwardly from a point above the lower side of the end wall 10 and being inclined downwardly toward a mediate point of the floor, there being an air chamber below the inclined part of the floor, said floor having air intake openings in the inclined portion thereof and a burner disposed above and in line with the inclined 15 portions, said air openings being diverged upwardly, said burner being arranged to direct flames substantially horizontally above the inclined surface having the openings therein.

6. An oil burning furnace including an end wall, a burner in said end wall, a floor for the furnace having a part thereof located close to, and beneath, the burner, said 25 part being inclined downwardly and forwardly, a second inclined portion extending forwardly and downwardly from a point below the first inclined part, said wall hav-

ing openings therein below the inclined 30 parts of the floor, and said last-named inclined part having air intake ports therein.

7. An oil burning furnace including an end wall, a burner in said end wall, a floor for the furnace having a part thereof located close to and beneath the burner, said 35 part being inclined downwardly and forwardly, a second inclined portion extending forwardly and downwardly from a point below the first inclined part, said wall having openings therein below the inclined 40 parts of the floor, and said last-named inclined parts having air intake parts therein, forwardly diverging deflectors mounted on opposite sides of the burner, said floor having air intake openings therein behind said 45 deflectors.

8. An oil burning furnace including an end wall, a burner carried by said wall, and a furnace floor extending from said wall in a plurality of successively lower stages in 50 line with the burner, certain of said stages having downwardly inclined upper surfaces, and one of said inclined stages having upwardly diverging air inlet openings therein.

GEORGE C. ADAMS.
